UNITED STATES PATENT OFFICE.

CHARLES TWINING, OF LOCUST POINT, NEW JERSEY.

AEROPLANE.

1,315,884.

Specification of Letters Patent.

Patented Sept. 9, 1919.

Application filed December 14, 1916. Serial No. 136,966.

To all whom it may concern:

Be it known that I, CHARLES TWINING, a subject of the King of Great Britain, and a resident of Locust Point, in the county of 5 Monmouth, in the State of New Jersey, have invented a new and Improved Aeroplane, of which the following is a full, clear, and exact description.

The present invention relates to aeroplanes, and more particularly means for elevating and controlling the path of movement of the aeroplane.

The object of my invention is to provide 10 a lifting plane for an aeroplane with means to operate the plane to impart thereto vertical and longitudinal movements and to provide the said plane with means whereby the downward movement of the plane will be resisted by the air, whereas the upward movement will be substantially free from atmospheric pressure.

A further object of my invention is to provide 15 an aeroplane with a group of superimposed lifting planes spaced apart from each other and operating independently, but with a certain time relation so that one or more of the said planes shall always present a closed air-resisting surface operating to exert pressure upon the air to raise the aeroplane, while others in the group are moving 20 without air resistance preparatory to exerting a lifting force.

A further object of my invention is to so arrange the lifting planes that they may be 25 deflected downwardly at their forward ends from a normal substantially horizontal position for the purpose of enabling the said planes to propel the aeroplane in a forward direction.

Further objects of the invention will appear 30 in connection with the following description of the construction, organization and mode of operation of that form of my invention illustrated in the accompanying drawings.

With the foregoing objects in view, my invention may be said to consist of an aeroplane provided with a substantially horizontal frame carrying a plurality of pivotally 35 supported slats with means for imparting to said frame upward and downward movements and movements in the plane of the frame, whereby the slats will be automatically opened as the frame is elevated and au-

tomatically closed while the frame is lowered.

My invention further consists of the devices and combinations of devices which will be hereinafter described and claimed.

In the accompanying drawings, Figure 1 shows in side elevation an aeroplane embodying the invention.

Fig. 2 shows a front end elevation.

Fig. 3 shows a section taken on the line 3—3 in Fig. 1 looking downward with most 65 of the parts in plan and with the ends of the auxiliary sails broken away.

Fig. 4 is a diagrammatic view illustrating in full lines one of the lifting and propelling planes as it has reached the upward limit of 70 its stroke and is about to be advanced longitudinally and forwardly, and illustrating in dotted lines the downward, rearward and upward movements from the position shown in full lines.

Fig. 5 is a detail of the construction of 75 the depending pivotally mounted slats and the check rail or guard.

Fig. 6 is an enlarged detail of a portion 80 of one of the side bars of the frame of one of the planes and illustrating the manner of pivotally connecting the slats thereto and to the check rail or guard, also illustrating a cushion to receive the shock incident to the closing of the check rail against the under 85 side of the frame.

Fig. 7 is a plan view of one of the pivoted truss frames.

Similar reference characters will be employed to designate corresponding parts. 90

In the drawings, 1 indicates the car; 2 the seat for the driver; 3 the supporting wheels, and 4 the engine, all of which may be of any suitable or preferred construction, the engine being preferably some form of internal combustion or gas engine and receiving 95 its fluid from a tank.

Supported vertically and rigidly from the car 1 are the uprights or stanchions 6, there being two of such stanchions located at 100 diametrically opposite sides of the car 1. In front of these uprights 6, there are two vertically extending uprights or stanchions 7 located at diametrically opposite points of the car 1 and pivotally connected at their lower ends, as at 8, to levers 9, there being two of these levers located at opposite sides 105 of the car 1 and pivotally connected at their

rear ends, as at 10, whereby the levers 9 may be raised and lowered and thus raise and lower the stanchions 7.

These stanchions 6 and 7 are suitably braced by the pivoted truss frames 10^a pivotally connected at 11 to lugs or bearings 12 carried by the stanchions 6 and 7, see Figs. 1, 2 and 7. The stanchions 6 are further braced by the guy ropes or stays 12 connected to the upper ends of the stanchions and at their lower ends to the car 1 rearwardly and forwardly of the stanchions 6.

The stanchions or uprights 7 are likewise strengthened and braced by means of the 15 transversely extending rods 10^b (see Fig. 2), and diagonally extending stays 13. At or near the lower ends, the stanchions or uprights 7 pass through guides 14 attached to the sides of the car 1 (see Figs. 1 and 2), by 20 means of which the lower ends of the stanchions 7 are held in position and yet are allowed to be moved up and down freely as required. The uprights 6 and 7 support suitable bearings in which are mounted 25 crank shafts 15 which at their outer ends are provided with sprocket wheels 16 and those crank shafts 15 which are supported by the stanchions 6 are provided with bevel gears 17, and the bevel gears 17 mesh with and are 30 driven by bevel gears 18 carried by vertically disposed shafts 19, the shafts 19 being mounted and supported in suitable bearings carried by brackets 20 supported by the uprights or stanchions 6 (see Fig. 1). The uprights or stanchions 7 carry crank shafts, 35 the outer ends of which are provided with sprocket wheels 21, and the sprocket wheels 21 are connected by sprocket chains 22 with the sprocket wheels 16 of the crank shafts 15.

40 From the foregoing description, it will be observed that a rotation of the vertical shafts 19 will impart through the bevel gears 17 and 18 a rotary motion to the sprocket wheels 16, which motion will be transmitted 45 by the sprocket chains 22 to the sprocket wheels 21 supported by the uprights or stanchions 7, and that thus the pairs of crank shafts supported in opposed relation to each other will be revolved simultaneously.

The vertical shafts 19 are driven from the engine 4 through a horizontal shaft 23 and bevel pinion 24 and a transversely extending shaft 25 carrying at its ends bevel gears 26 55 meshing with bevel gears 27 mounted upon the vertical shafts 19.

Each pair of crank shafts carries and operates a lifting and propelling plane, there being in the machine shown in the drawings 60 six such lifting and propelling planes superimposed one above another in a vertical direction and substantially parallel to each other and preferably extending longitudinally of the aeroplane. These lifting planes 65 each consist of a pair of longitudinally ex-

tending side bars 28 arranged in parallel relation to each other and pivotally mounted upon a pair of crank shafts and designed to partake of the movements of the said crank shafts.

70

Pivotaly connected to each pair of side bars 28 are transversely extending slats or vanes 29, the slats or vanes 29 being of a length to extend transversely between each pair of cross bars 28, and impinge upon and 75 contact with the under surface of the cross bars 28. The slats or vanes 29 are pivotally mounted upon the under surface of the cross bars 28 a distance apart substantially equaling their depth, so that when closed and in 80 contact with the under surface of the bars 28, they will form a practically closed surface to act upon the air and exert a lifting force when the planes are depressed.

75

The slats or vanes 29 may be constructed 85 of a suitable wire frame 30 and a thin, strong and suitable fabric 31 sufficiently light to permit freedom of movement of the slats or vanes in their opening and closing action and sufficiently strong to produce an 90 effective lifting surface against the pressure of the air produced by the downward movement of the planes.

80

The construction of the plane thus described is such that when it is moved by the 95 crank shafts to impart thereto vertical and longitudinal movements in parallelism, the slats or vanes 29 on a forward movement will automatically close under the pressure of the air against them, and when closed the 100 downward movement will exert pressure upon the air, exerting a lifting force, and upon the upward movement the slats or vanes will automatically open so as to eliminate any air resistance to the free upward 105 movement.

95

In order that the opening and closing movements of the slats or vanes shall be uniform and to eliminate shocks and noise incident to their closing movement, the lower 110 edges are preferably pivotally connected to parallel check bars 32, which check bars will carry at their opposite ends cushions 33 arranged to engage cushions 34 carried by adjusting screws 35 set in the opposite ends of 115 the bars 28, (see Figs. 1, 5 and 6).

110

A convenient means of pivotally connecting the slats or vanes 29 to the bars 28 and the check bars 32 is shown in Fig. 6 and comprises staples 36 and 37 carried by the 120 bars 28 and the check bars 32 respectively and engaging the upper and lower parallel members of the wire frame 30. This provides a freedom of movement and a relatively strong connection.

120

For the purpose of raising and lowering the levers 9 and thus raising and lowering the stanchions or uprights 7, I provide double toggles 37^a which are pivotally connected to the levers 9 and pivotally mounted upon 130

125

a suitable support at their lower ends, which toggles are operated by threaded rods 38 which by means of suitable bevel gearing 39 and a hand-wheel 51 located adjacent to the 5 seat 2, raise and lower the levers 9, so as to cause the lifting and propelling planes to be deflected from a horizontal position. The levers 9 are pivotally hung upon the shaft which carries the bevel gear 39.

0 When the forward ends of the lifting and propelling planes are depressed from the position shown in Fig. 1, they will operate not only to exert a lifting pressure on the air, but also a pushing pressure thereon in a 15 downward and rearward direction, thus causing the aeroplane to move in a forward direction.

A suitable rudder 40 is provided pivotally mounted as at 41 to a rearwardly extending 20 frame 42 supported from the vertical uprights or stanchions 6, and this rudder is operated by means of cords 43 extending forwardly and around pulleys 44 downward to a drum 440 operated by a wheel 441.

25 As shown in the drawings, there are six of the lifting and propelling planes, and the crank shafts operating them are angularly disposed with relation to each other so that their movements will be sixty degrees apart, that is to say, there will be a difference of 30 sixty degrees in the angular position of the respective crank shafts, as clearly indicated in Fig. 1 of the drawings, by which arrangement the lifting and propelling planes are 35 operated in such time relation to each other that reading downward from the top of Fig. 1 the lifting and propelling planes will operate in pairs traveling downward and upward alternately and forward and backward 40 alternately, and thus as one plane exerts pressure on the air the one immediately below it will be relieving pressure, all as will be clear from an inspection of Fig. 1 of the drawings.

45 In order to supplement the air supporting surface while traveling forward, and while volplaning and to assist in stabilizing and supporting the machine, I provide the laterally disposed sails 45 (see Fig. 2 of the drawings), which are pivotally mounted upon a transversely extending rod 46, at a point above the center of these sails, the arrangement being such that they will drop by gravity and will normally assume the position shown in Figs. 1 and 2, but when the machine is traveling forward the air pressure upon the lower portion of the sails 45 will rock them about the shaft 46 and cause them to assume the position shown in 55 dotted lines in Fig. 1, there being suitable stops 47 connected to the stanchions or uprights 6 to maintain the sails 45 in the dotted line position when the machine is being propelled forwardly or when volplaning.

60 65 As the sails 45 are free to move as the pres-

sure of the wind compels movement they will automatically act to counteract any tendency of the machine to drop or to turn over sidewise thus providing automatic stabilizing means.

70

The sails 45 are automatically operative and may adjust themselves to the pressure of the air thereon, and they will be preferably connected to cords 48 running over a pulley 49 and coiled at their lower ends to the 75 spring-controlled roller 50, whereby the slack in the cord 48 will be automatically taken up. This cord 48 will limit the forward motion of the lower part of the sails. Also, by means of the cord 48 the operator 80 may at any time swing the sails to the dotted line position.

80

In operation, assuming the machine to be in the position indicated in full lines in Fig. 1, upon the engine being started, the rotation 85 of the shafts 19 will impart rapid revolving movements to the respective crank shafts carrying the lifting and propelling planes. The movements of the planes will cause an automatic opening and closing movement of 90 the slats or vanes 29, the closing movement occurring at the beginning of the downward movement of the planes.

90

When the slats or vanes are closed, the downward movement of the planes causes a 95 pressure upon the air sufficient to lift the machine, and it is understood that at all times this downward or lifting pressure will be produced by a plurality of the planes, while others are relieved from air pressure 100 and are moving upward and forward preparatory to a downward or lifting movement.

100

While the aeroplane is ascending, the planes will preferably be supported in a 105 substantially horizontal position, but having reached the desired altitude the levers 9 may be lowered, thus lowering the forward ends of the planes which will then exert a back pressure upon the air, causing the machine to move forward at which time the sails will be automatically rocked upon the rod 46 and caused to assume the position indicated by dotted lines in Fig. 1, thus providing auxiliary supporting surfaces. When 110 it is desired to descend, the engine may be shut off and at that time the planes will all automatically close up and co-operate with the sails, providing means whereby the machine may be volplaned to earth.

110

120 Having thus described my invention, I claim as new and desire to secure by Letters Patent:

1. In an aeroplane, in combination, a car, a support carried by the car, a lifting plane carried by said support comprising a frame and a plurality of slats pivotally mounted and depending from said frame and arranged in parallel relation to each other, and means to move said 125

120

130

plane up and down and in its own plane in opposite directions at right angles to the planes of the depending slats.

2. In an aeroplane, in combination, a car, a support carried by the car, a lifting and propelling plane carried by said support and vertically and longitudinally movable on said support, means for moving said plane vertically and longitudinally, the longitudinal movements being in parallel planes and a plurality of pivotally supported slats suspended from the planes.

3. In an aeroplane, in combination, a car, a support carried by the car, a lifting and propelling plane carried by said support and vertically and longitudinally movable on said support, means for moving said plane vertically and longitudinally, the longitudinal movements being in parallel planes, and a plurality of pivotally supported slats suspended from the planes, the distance between the pivotal connection of adjacent slats substantially equaling the depth of said slats.

25 4. In an aeroplane, in combination, a car, a support carried by the car, a plurality of lifting and propelling planes mounted upon said support one above the other in parallel relation to each other, a plurality of swinging slats pivotally mounted and depending from said planes, and means to impart longitudinal and vertical movements to said planes, the longitudinal movements being in parallel planes.

30 5. In an aeroplane, in combination, a car, a support carried by the car, a plurality of lifting and propelling planes mounted upon said support one above the other in parallel relation to each other, a plurality of swinging slats pivotally mounted and depending from said planes, means to impart longitudinal and vertical movements to said

planes, the longitudinal movements being in parallel planes, the movements of adjacent planes being timed relatively to each other so that their position at any given time shall be substantially in opposite directions.

6. In an aeroplane, in combination, a car, a support carried by the car, a plurality of lifting and propelling planes mounted upon said support one above the other in parallel relation to each other, a plurality of swinging slats pivotally mounted and depending from said planes, means to impart longitudinal and vertical movements to said planes, and means to raise and lower the group of planes at one end whereby to change their angular position with relation to the horizontal.

7. In an aeroplane, in combination, a car, a support carried by the car, a plurality of lifting and propelling planes mounted on said support one above the other in parallel relation to each other, a plurality of swinging slats pivotally mounted and depending from said planes, means to impart longitudinal and vertical movements to said planes while retaining their parallelism, and a pair of swinging sails pivotally connected to the support, the pivotal point being nearer one end of the sails than the other, and a stop limiting the pivotal movement of said sails in one direction.

8. In an aeroplane, in combination, a car, a supporting plane mounted on said car and a pair of swinging sails pivotally mounted upon opposite sides of the car the pivotal point being nearer one end of said sails than the other, said swinging, pivotally-mounted planes being free to swing automatically about their pivots in use, thereby to operate as stabilizing planes.

CHARLES TWINING.
